FOUR-WAY REVERSE CYCLE VALVE

Irvin E. Wiegers, St. Louis, Mo., assignor to Alco Valve Company, St. Louis, Mo., a corporation of Missouri

Filed Aug. 26, 1957, Ser. No. 680,282

12 Claims. (Cl. 137—599.1)

The present invention relates generally to valves for controlling fluid flow, and more particularly to a novel four-way valve for reverse cycle operation in a closed fluid flow system.

Briefly, the invention contemplates a novel four-way valve having a main inlet port, a main outlet port, and a pair of combination inlet-outlet ports, the arrangement being such that the main inlet port may be communicated directly with one, and the main outlet port with the other, of the combination ports and then operated so as to communicate the main outlet port with the one, and the main inlet port with the other, of the combination ports.

The present valve is primarily intended for applications where a substantial pressure differential will exist between the main inlet and the main outlet, this pressure differential to be utilized, not only to maintain the valve in a selected condition of flow control, but also to effect changes from one control condition to the other.

The four-way valve of the present invention comprises an arrangement including two separate two-way valves, one of these two-way valves being adapted for direct actuation and the other being adapted for indirect or "slave" actuation following the direct actuation of the one valve. The direct actuation is preferably effected by means of a piston arrangement in conjunction with a diverting valve which selectively communicates the piston cylinder with either the relatively high pressure maintained at the main inlet port or with the relatively low pressure maintained at the main outlet port. A dual check-valve assembly cooperates with the directly actuated two-way valve to provide increased dependability of operation.

It is apparent from the foregoing that the primary object of the present invention is to provide a novel four-way valve which is adapted to direct a pressure flow in a selected one of two directions and to receive a return flow from the other.

It is another object of the invention to provide a novel four-way valve which utilizes pressure differences existing therewithin for selectively maintaining a pressure seal between different fluid passage portions of the valve.

It is another object of the invention to provide a novel four-way valve which incorporates a high pressure and a low pressure chamber and which incorporates means for communicating either of these chambers selectively with a pressure responsive element for reversing a fluid flow condition.

It is another object of the invention to provide a novel four-way valve which comprises both a directly and an indirectly actuated two-way valve and which incorporates a dual check valve for cooperation with the directly actuated two-way valve.

The foregoing, along with additional objects and advantages, will be apparent from the following description of a specific embodiment of the device as depicted in the accompanying drawing, in which:

Figure 1 is a schematic representation of a closed fluid

2

flow system incorporating the reverse cycle valve of the present invention;

Figure 2 is a top plan view, partly in section, showing a reverse cycle valve constructed in conformance with the teachings of the present invention;

Figure 3 is a sectional view taken generally along the line 3—3 of Figure 2; and

Figure 4 is a fragmentary sectional view drawn to reduced scale, illustrating a modified form of the invention.

Directing more particular attention to the details of the drawing through use of the reference characters applied thereto, the numeral 10 designates generally a reverse cycle valve constructed in conformance with the present invention. The valve 10 includes a main body 12, preferably of cast or forged metal, formed so as to define two parallel barrels 14 and 16. Considering first the barrel 14, it will be noted from Figure 3 that a main outlet port 18 fitted with an outlet conduit 20 communicates with an outlet chamber 22 formed centrally of the length of the bore 14. As is clear from this figure, the chamber 22 defines a minimum diameter of the bore 14 whereby shoulders 24 are provided for seating abutment with valve sleeves 26 and 28 inserted from opposite ends of the bore 14 and pressed into place as illustrated. The sleeves 26 and 28 preferably take the shape clearly indicated in Figure 3, and each is provided with an annular seat 30 of resilient material retained by bent over flanges 32 forming integral portions of the sleeves 26 and 28.

A valve assembly 34 is disposed for reciprocation in the bore 14. The assembly 34 includes a valve head 36 having a tapered portion 38 formed for seating engagement with the seat 30 disposed in the valve sleeve 26. The valve head 36 is extended upwardly a predetermined distance and is surmounted by a piston head 40 provided with conventional sealing grooves 42.

A valve stem 43, integral with the valve head 36, extends downwardly therefrom through the outlet chamber 22 wherein it slidably mounts check valves 44 and 45 biased by means of a relatively light compression spring 46 toward respective closing engagement with the valve sleeves 26 and 28. Below the sleeve 28, the valve stem 43 is fitted with a valve head 47 having a tapered portion 48 for seating engagement with the seat 30 disposed in the valve sleeve 28. The head 47 is fitted onto a reduced portion 50 and positioned against a shoulder 52, being then staked in place as indicated at 54. A still further reduced portion 56 of the valve stem 43 extends downwardly through a guide 58 retained in a counterbored portion 60 of the bore 14 by means of a closure plate 62 welded into place as shown.

It may be mentioned at this point that the opposite end of the bore 14, as well as both ends of the bore 16, are similarly counterbored and provided with identical closing discs 62.

Directing attention now to the bore 16, it will be observed from Figure 3 that this bore also has a central portion of minimum diameter, which portion defines a main inlet chamber 64 provided with a main inlet port 66 in communication with an inlet conduit 68.

A pair of identical valve sleeve assemblies 70 are inserted from opposite ends of the bore 16 and are pressed into place against shoulders 72 formed at the upper and lower ends of the inlet chamber 22. These assemblies 70 include sleeve-like cages 74 formed at one end to receive annular valve seats 76, these seats 76 being retained by inturned flanges 78, similar to the flanges 32 on the valve sleeves 26 and 28 aforementioned. At their ends opposite the flanges 78, the members 74 are provided with inwardly extending flanges 80 for retaining compression springs 82 in the manner clearly illustrated in Figure 3.

A ball valve 84 adapted for seating engagement with either of the seats 76 disposed in the sleeve assemblies 70 is interposed between the two compression spring 82. It will be understood that each of the springs 82 is under continuous compression and that they are so balanced as, in the absence of other forces, to position the ball valve 84 approximately midway between the seats 76. Preferably, the member 74 of the valve sleeve assemblies 70 are staked into place as indicated at 86.

The portion of the barrel 16 below the sleeve assemblies 70 is communicated through a combination inlet-outlet port 88 with a conduit 90, and also through a cross port 92, formed in a common wall 94 between the barrels 14 and 16, with that portion of the barrel 14 below the valve sleeve 28. Similarly, the portion of the valve 16 above the valve sleeve assemblies 70 is communicated through a combination inlet-outlet port 96 with a conduit 98, and also through a cross port 100, formed in the common wall 94, with that portion of the barrel 14 which is above the valve sleeve 26. In further connection with the location of the cross port 100, it will be noted from Figure 3 of the drawing that this port communicates with that portion of the barrel 14 which is below the piston 40, the head portion 36 being sufficiently elongated to dispose the piston 40 above the cross port 100 even when the tapered portion 38 is seated against the seat 30 disposed in the valve sleeve 26.

The body 12 of the valve 10 includes a boss portion 102 located at the level of the chambers 22 and 64 and extending transversely in respect to the length of the body 12 as clearly illustrated in Figure 2 of the drawing. The boss 102 is provided with a main passage 104 which communicates at its inner end with the main inlet chamber 64. At its outer end, the passage 104 is counterbored so as to provide successive enlarged portions 106, 108, 110, 112 and 114. An offset passage 116 communicates the outlet chamber 22 with the portion 112 of the main longitudinal port 104.

A valve seat 118 is pressed into the portion 106 of the passage 104 and a valve seat 120 is pressed into the portion 110, thereby defining a chamber in the open portion 108. A ball valve 122 is disposed in the open chamber portion 108 so as to be movable between the seats 118 and 120. Preferably, the size of the ball valve 122 is such that it will remain substantially on the center line of the longitudinal passage 104 and thus may be selectively seated against either of the seats 118 and 120.

A passage 124 communicates the chamber portion 108 of the passage 104 with that portion of the barrel 14 which is above the piston 40, and it will be understood that this passage 124 may be defined either wholly within a wall of the body 12 or by an external conduit. In other words, this intercommunication between different portions of a valve body is conventional, and is depicted schematically in the drawings by means of the broken line 26 extending between Figures 2 and 3.

The depicted embodiment of the four-way valve 10 includes an actuating solenoid assembly 128. The assembly 128 comprises a conventional solenoid coil 130 enclosed in the usual case 132, but disposed over a special core assembly 134. The assembly 134 includes a tubular member 136 fitted into the recessed portion 114 of the passage 104 and secured therein as by welding 138. At its opposite end, the tubular member 136 is provided with a plug 140 which is pressed into place and which has an extended threaded portion 142 fitted with a nut 144 for retaining the solenoid assembly 128 thereon. An armature 146, provided at one end with a spring well 148 in which is disposed a compression spring 150 and provided at the opposite end with a pin 152 extending co-axially therebeyond, is disposed for reciprocation in an armature chamber defined by that portion within the tubular member 136 below the plug 140 and including also the portion 112 of the passage 104. By this arrangement, the pin 152 is able to force the ball valve 122 against the seat

118, which action is induced by the spring 150 in the absence of energization of the solenoid coil 130. Upon energization of the solenoid 130, however, the armature 146 is retracted against the spring 150 so as to withdraw the pin 152 from the ball 122 and allow the latter to seat against the seat 120.

Operation.—The reversible four-way valve 10 is particularly adapted for use in reversible fluid flow systems, such as those employing heat pump or refrigerating cycles. Such a system is represented schematically in Figure 1 of the drawings wherein the valve 10 is shown having the conduits 68 and 20 connected into the pressure and suction sides, respectively, of a compressor 154, and having the conduits 90 and 98 connected into opposite sides of a closed external fluid flow circuit comprising heat exchangers 156 and 158 and an expansion valve 160.

If it be now assumed that the solenoid coil 130 is energized so as to draw the armature 146 and its pin 152 upwardly away from the ball valve 122, the relatively high pressure which exists in the inlet chamber 64 by virtue of its connection with the pressure side of the compressor 154 will be established also in the extreme upper end of the barrel 14 above the piston 40. If it be further assumed that the valve assembly 34 and the ball valve 84 are in the positions illustrated, pressure flow entering the inlet chamber 64 through the main inlet port 66 will pass upwardly through the upper sleeve-like spring cage assembly 70 and outwardly through the port 96 and through the conduit 98 toward the heat exchanger 158. Passing through the device 158, the valve 160, and the heat exchanger 156, the fluid will return to the valve 10 through the conduit 90 to enter the lower end of the barrel 16. From this point the fluid will flow through the cross passage 92 into the lower end of the barrel 14 thence upwardly through the valve sleeve 28 and past the check valve 45 into the outlet chamber 22, and on outwardly through the main outlet port 18 and the conduit 20 to return to the suction side of the compressor 154. It will be understood that the lightly loaded check valve 45 gives way readily to accommodate such flow.

Under the conditions above described and as clearly illustrated in the drawing, it will be noted that high pressure is maintained not only above the piston 40, which is integral with the valve head 36, but also above the ball valve 84. Moreover, the dual check valves 44 and 45, lightly loaded as they are, are ineffective to withstand substantial pressure differentials between the outlet chamber 22 and the spaces interiorly of the sleeves 26 and 28. As a result, a reduced pressure is extended both to the underneath side of the valve head 36 and to the underneath side of the ball valve 84. Hence, it is clear that the pressure differential which exists between the main inlet chamber 64 and the main outlet chamber 22 is influential in maintaining the valve elements 36 and 84 in a desired seated condition, as illustrated.

If it be now assumed that the solenoid coil 130 is de-energized, the spring 150 will act to drive the armature 146 and its pin 152 downwardly so as to force the ball valve 122 against the seat 118. Displacement of the ball 122 from the seat 120 serves to communicate the pressure chamber in the extreme upper end of the barrel 14 with the main outlet chamber 22. The resulting reduction in pressure exerted against the upper end of the piston 40 enables the high pressure, which is still maintained on the annular underside of the piston 40, to displace the whole assembly 34 upwardly so as to open the valve 38 in addition to the valve 48. This causes the upper end of the barrel 16 to be suddenly communicated through the cross passage 100 to the valve sleeve 26, with only the check valve 44 obstructing direct communication with the low pressure outlet chamber 22. Under these conditions, the pressure suddenly exerted on top of the check

valve 44 is sufficient to move it downwardly from engagement with the valve sleeve 26 thereby establishing flow through the latter to the outlet chamber 22 and, at the same time, providing additional biasing force through the spring 46 to close the check valve 45 against the upper end of the valve sleeve 28. The inherent tendency of mutually loaded, free floating valve members, such as the combination of elements 44, 45 and 46, to favor flow through one port or the other serves to maintain the elements in the new positions to which they are thus moved.

The open condition of both the valves 38 and 48 tends also to cause pressure equalization above and below the ball valve 84 so that the normal balancing action of the springs 82 will cause the ball 84 to seek a centered position between the seats 76. With both the valve assembly 34 and the ball valve 84 in mid-position, the flow of fluid is necessarily short-circuited from the inlet chamber 64 to the outlet chamber 22. However, with the check valve 44 being in open position, as above described, the short-circuit will be by way of the upper spring cage 74, the cross passage 100, and the valve sleeve 26 to the chamber 22. The presence of the check valve 44, of course, effects a pressure differential between the pressure which exists in the chamber 22 and that which exists in the sleeve 26 and immediately below the piston 40. Inasmuch as it is the pressure of the chamber 22 which is communicated to the space above the piston 40, it is clear that a net force is available to move the valve assembly 34 to its uppermost position wherein the valve 48 will be seated against the seat 30. As the pressure at the lower end of the barrel 16 builds up, due to the valve head 47 being seated, and as the pressure at the upper end of the barrel 16 is lowered due to the valve head 36 being unseated, the generally upward flow of fluid past the ball valve 84 and the attendant pressure drop around the ball and the upper seat 76 will cause the former to be seated in its uppermost position. It will be noted once more, that with the valve head 47 and the ball valve 84 seated upwardly, the distribution of pressures within the barrels 14 and 16 is again such as to maintain a desired closed condition. In this new condition the valve 10 provides pressure flow directly through the conduit 90 to the heat exchanger 156 and receives the return flow from the heat exchanger 158 through the conduit 98.

When once again it is desired to revert the valve 10 to the illustrated condition, the solenoid coil 130 is again energized so as to cut off communication of the extreme upper end of the barrel 14 with the outlet chamber 22 and re-establish communication of this piston chamber with the inlet chamber 64. The resulting high pressure established above the piston portion 40 will then cause the assembly 34 to be moved downwardly, first to a mid-position which will be effective, once again, to shift the dual-check valves 44 and 45 so as to favor flow upwardly past the valve 45. This movement will then be followed by a sequence of movement which will be just the reverse of that above-described, resulting finally in the establishment of the illustrated condition of the valve 10.

It will be noted that there is no mechanical connection between the valve assembly 34 and the movable ball valve 84. It will also be noted that, whereas initial movement of the valve assembly 34 is directly instigated by the establishment of positive pressure differentials above and below the piston portion 40, subsequent movements of this assembly, as well as movement of the ball valve 84, are induced by a combination of pressure differential and dynamic flow conditions which result from changes in position of the dual check valve assembly 44, 45, 46.

Although the valve 10 constructed as above-described and as depicted in Figure 3 of the drawing represents a preferred embodiment of the present invention, certain aspects thereof are delineated in modified form in the fragmentary cross section of Figure 4. The modified valve designated generally by the numeral 162, incorpo-

rates a shuttle valve assembly 164 in place of the previously described parts 44, 45, 46.

The assembly 164 comprises dual valve flanges 166 and 168 formed on tubular thimble portion 170 slideable on the valve stem 43. The flanges 166 and 168 are so spaced that abutment of one of them with the respective sleeve 26 or 28 will leave the other sleeve open to passage of fluid.

The functioning of the valve 162 is similar in principle to that of the valve 10, but lacks the automatic control of pressure drop provided by employment of the spring 46.

Clearly, there has been described a reverse cycle valve and a modification thereof which together fulfill the objects and advantages sought therefor.

It is to be understood that the foregoing description and the accompanying drawing have been given only by way of illustration and example. It is further to be understood that changes in the elements, rearrangement of parts, and the substitution of equivalent elements, all of which will be obvious to those skilled in the art, are considered to be within the scope of the present invention, which is limited only by the claims which follow.

What is claimed is:

25. A four-way reverse cycle comprising, in combination, a main valve body having a high pressure chamber provided with an inlet port, a source of high pressure fluid communicating with the inlet port, a low pressure chamber provided with an outlet port, the valve body including a pressure housing, first means in the body for communicating the pressure housing with the low pressure chamber including a first valve seat, a movable wall in the housing with a first space between one side of the wall and the valve seat and a second space on the other side of the wall, second means in the body for communicating the first space with the high pressure chamber, a second valve seat between the first inlet port and the second communicating means, third means in the body for communicating the low pressure chamber with the high pressure chamber, a third valve seat between the third communicating means and the outlet port, an auxiliary inlet-outlet port communicating with the second communicating means and an auxiliary inlet-outlet port communicating with the third communicating means, a first double acting valve assembly for making seating and unseating engagement with the first and third valve seats, a second valve assembly for making seating and unseating engagement with the second and fourth valve seats, means for alternately communicating the second space in the housing with the low pressure chamber and the high pressure chamber, the movable wall being movable in response to pressure differentials in the two spaces, one of the valve assemblies being movable between seating and unseating positions respecting its valve seats in response to movement of the movable wall, and a dual directional check valve arrangement in the path of fluid flow through the chamber having the one valve assembly, the check valve assembly being operable upon movement of the one valve assembly between positions blocking and unblocking the second and third communicating means, the other valve assembly being operable to seat against one of its valve seats in response to pressure differentials created by the check valve.
60. 2. The valve of claim 1: the check valve arrangement being in the path of fluid flow through both the first and the third valve seats and operable to alternately block one while unblocking the other and vice versa, the check valve means when in unblocking position relative to one of the seats being close enough to that valve seat to cause a pressure drop in fluid passing through that seat, and the said other valve assembly being responsive to the blocking by the check valve means of one seat for closing 70 the passage means between the other seat and the inlet

and opening the passage means between that other seat and the outlet.

3. The combination of claim 1 wherein the dual directional check valve arrangement comprises a pair of axially separated discs adapted to partition the outlet chamber, and a compression spring interposed between said discs.

4. The combination of claim 3 wherein the double-acting valve assembly actuated by the pressure responsive means comprises a valve rod having axially spaced valve heads thereon, the dual directional check valve being slidably mounted on said valve rod intermediate said valve heads.

5. A fluid flow system having four-way reverse cycle valve means comprising, in combination, means defining a main inlet chamber and a main outlet chamber, a fluid source, means for communicating the fluid source with the main inlet chamber, means for providing fluid communication between the two chambers, a first two-way valve means associated with said main inlet chamber for directing a fluid flow therefrom in a selected direction, a second two-way valve means associated with said main outlet chamber for directing a fluid flow therewith from a selected direction, said first two-way valve means comprising a movable member engaged on opposite sides by yieldable spring means, differential pressure responsive means for operating said second two-way valve means, means including diverting valve means for communicating a selected one of said main inlet and main outlet chambers with one side of said differential pressure responsive means, and means communicating with the other side of said differential pressure responsive means including a floating dual directional check valve assembly responsive to change of flow in the main outlet chamber for establishing a different pressure on the other side of said differential pressure responsive means.

6. The combination of claim 5 wherein the second two-way valve means includes axially spaced openings in the main outlet chamber, said openings being provided with valve seats, and a valve rod rigidly mounting a valve head for each of said openings, and wherein the floating dual directional check valve assembly comprises axially spaced valve discs slidably mounted on said valve rod intermediate said openings, and a compression spring interposed between said valve discs so as to bias each toward closing relation with a respective one of said openings.

7. The combination of claim 6 wherein the valve heads are disposed outside the main outlet chamber and the dual directional check valve assembly is disposed inside the main outlet chamber.

8. A reverse cycle valve comprising, in combination, a four-way valve having a high pressure chamber provided with an inlet, a high pressure fluid source connected to the inlet, a low pressure chamber provided with an outlet, and a pair of auxiliary inlet-outlet ports, means connecting said auxiliary inlet and outlet ports between said high pressure and low pressure chambers, movable means associated with said chambers for directing flow from the high pressure chamber to the low pressure chamber by way of said auxiliary ports, means including piston means for actuating said four-way valve so as to reverse the direction of flow through the auxiliary ports, a diverter valve for communicating one side of said piston

means alternately with said high pressure chamber and said low pressure chamber, and dual directional check valve means movably disposed in said low pressure chamber for establishing a pressure differential across said piston means.

9. The combination of claim 8 wherein the low pressure chamber has opposite end openings for communication with respective auxiliary ports, and wherein the dual directional check valve means comprises a pair of valve discs, and resilient means biasing said discs toward closure of said end openings.

10. A fluid flow system having a four-way reverse cycle valve comprising, in combination, a main valve body defining two barrels, means intercommunicating said barrels at spaced points in the longitudinal extent of the barrels, a pair of valve seats disposed in each of said barrels within corresponding portions of the barrels between adjacent intercommunicating means, movable valve means disposed in each of said barrels for selective alternate seating engagement, respectively, with the correspondingly disposed valve seats aforesaid, at least one of said valve means including a resiliently floated valve member, means defining a main inlet chamber in one barrel and a main outlet chamber in the other, said chambers each comprising that portion of its barrel which extends between the pair of seats therein, an individual external conduit connected to each of said chambers, means defining at least two combination ports, one of said ports serving to communicate both of said barrels at corresponding points in one direction beyond the chambers with a third external conduit, the other of said combination ports serving to communicate both of said barrels at corresponding points in the other direction beyond the chambers with a fourth external conduit, pressure responsive means including piston means connected to one only of said movable valve means for displacing the latter relative to its valve seats, means for selectively communicating the piston means alternately with said chambers, and a dynamic pressure loss device in the main outlet chamber for providing a pressure difference at opposite ends of said piston means.

11. The combination of claim 10 wherein the valve seats associated with the main outlet chamber are in axial alignment and face away from each other, wherein the movable valve means associated with the main outlet chamber includes a pair of closure elements disposed outside the main outlet chamber, one on each side of the pair of valve seats associated with the main outlet chamber, and wherein the dynamic pressure loss device comprises a pair of check valve flanges, each adapted to close one of the two valve openings in the main outlet chamber.

12. The combination of claim 11 wherein the check valve flanges are resiliently biased away from each other toward closure of both of the valve openings in the main outlet chamber.
